PAGE 4

Fig. 4.

Fig. 5.

FIG. 1 is a front elevational view of a tractor mounted cotton harvester showing our new design;

FIG. 2 is a rear elevational view thereof;

FIG. 3 is a left front perspective view thereof;

FIG. 4 is a right front perspective view thereof; and

FIG. 5 is a view similar to FIG. 4 showing the basket in a dumping position of a tractor mounted cotton harvester.

The dominant features of our design reside in the portions shown in full lines.

We claim:

The ornamental design for a tractor mounted cotton harvester, as shown and described.
